UNITED STATES PATENT OFFICE.

FRANKLIN DAVID WALPOLE, OF MCKENZIE, TENNESSEE.

HEEL PLATE FOR SHOES AND THE LIKE.

Application filed June 30, 1923. Serial No. 648,659.

This invention relates to certain improvements in heel plates for shoes and the like; and the nature and objects of the invention will be readily recognized and understood by those skilled in the art to which it relates in the light of the following explanation and detailed description of the accompanying drawings illustrating what I at present consider to be the preferred embodiment or mechanical expression of the invention from among various other forms, arrangements, combinations and constructions of which the invention is capable within the spirit and scope thereof.

An object of the invention is to protect the feet of a wearer from rough, uneven interiors or inner soles commonly encountered in foot wear; and more particularly to protect the heel of the foot from contact with and injury by a rough, uneven inner surface at the heel of a shoe, such as may be occasioned by projecting nails, tacks or the like.

A further object of the invention is to provide for the treatment of the feet and body through the heels, by means positioned within footwear at the heels thereof for engagement with the heels of a wearer.

A further object of the invention is the provision of heel plates for mounting within shoes at the heels thereof, which form a protection for the heels of the wearer and also form containers or carriers for medicaments for treating the feet and body of the wearer.

A further object of the invention is to provide as a new article of manufacture, a soft metal heel protecting plate adapted to be placed within a shoe at the heel thereof and to receive and conform to the foot of a wearer, and which plate is formed to carry a medicament for treatment of the foot of a wearer in engagement therewith.

With the foregoing and various other objects and results in view, which other objects and results will be readily apparent to those familiar with this art, the invention consists in certain novel features in construction and in combination and arrangement of elements, as will be more particularly specified and pointed out hereinafter.

Referring to the accompanying drawings:

Fig. 1 is a plan view of the upper or foot receiving and contacting face of a heel plate of the invention.

Fig. 2, is a plan view of the bottom or shoe engaging side of the invention.

Fig. 3, is a transverse section through a heel plate taken on the line 3—3 of Fig. 1.

Fig. 4, is a plan view of a blank in open position from which a heel plate is formed.

In the illustrated example of one possible form of the invention presenting the broad principles and features thereof, a protecting and medicament carrying heel plate A is shown in Figs. 1, 2 and 3 of the drawings. The plate A is formed of the proper size and shape to fit into a shoe at the heel thereof and rest in flat position on and covering the inner surface of the shoe heel. Preferably, the heel plates A are constructed from so-called soft metal materials such as zinc and copper which are readily bendable, for a purpose appearing and explained hereinafter.

Each plate A is formed of an upper ply 10 providing the upper or heel receiving and engaging surface, and a lower ply 11 providing the shoe engaging face or surface, of the plate. The upper and lower plies 10 and 11 are formed of a relatively thin soft metal and superposed and joined together in fixed heel plate forming relation. A strip or layer of felt 12, or any other suitable or desired absorbent material, is interposed between the upper and lower plies 10 and 11, and is formed of substantially the shape and size of the plate A so as to extend throughout the plate between and covering the opposite interior faces of the plies 10 and 11, as clearly shown in Fig. 3 of the drawings. The upper heel receiving ply 10 of the plate A is provided with a series of apertures or bores 14 extending therethrough and exposing the felt absorbent strip 12 in the plate A. It will be understood that any desired number and arrangement of apertures 14 can be provided, although it is preferable that these apertures be arranged over the major portion of the ply 10 to come in contact with as large an area of a heel received by the plate as possible. A preferred arrangement and spacing thereof over the plate A is shown in Fig. 1 of the drawings.

A series of V cuts are formed at spaced intervals in the under or lower shoe engaging ply 11 of plate A, with the apexes thereof toward the forward edge 15 of the plate,

to form a series of pointed shoe engaging teeth 16, by bending the same outwardly a slight distance from the surface of the ply 11. The teeth 16, so formed, and positioned are particularly shown by Fig. 3 of the drawings.

One manner of forming the heel plate A is shown in Fig. 4 of the accompanying drawings, in which the upper and lower plies 10 and 11 are constructed from a single one-piece blank B having a transverse bending line 17 intermediate the ends thereof to divide the blank B into the plies 10 and 11, and to form the front or forward edge of the plate A when the blank is folded into plate forming relation. The portion of the blank B forming the upper ply 10, is provided with an edge flange 18. The blank B can be formed by cutting, stamping, or 20 any other suitable method, and the apertures 14 and teeth 16 are formed therein in the proper positions, as shown in Fig. 4. To construct a plate A from the blank B, a felt absorbent strip 12 is placed in position 25 on and covering the portion of the blank forming the upper ply 10, and the portion forming ply 11 is then bent along the line 17 over onto and covering the strip 12 and ply 10. In this position the flange 18 is then 30 bent up over and onto the ply 11 to fix and secure the plies 10 and 11 with the felt strip 12 interposed therebetween, into position and relation forming a heel plate A. The flange 18 thus forms and provides the curved 35 rear edge portion of the plate A adapted to fit and conform to the shape of the back of a shoe.

In operation and use of the invention, a heel plate A is placed in a shoe at and covering the heel portion thereof with the edge 40 15 of the plate forming the forward end thereof and the curved portion provided by the flange 18 forming the rear end conforming to the curvature of the back of the shoe, 45 as will be readily understood. The plate A is placed in a shoe with the lower ply 11 thereof on and against the inner surface of the shoe and the forwardly extending pointed teeth 16 engaging the shoe and preventing 50 the plate from creeping forward from proper position. The upper ply 10 of the plate with the apertures 14, is positioned to receive the heel of the foot, and due to the soft metal of which the plate is formed it 55 will conform to the shape and contour of the heel under the pressure to which it is subjected in use, and thus form a smooth seat or pocket which naturally and comfortably receives the heel and protects the 60 same from any roughness on the interior of the shoe at the heel thereof. The felt absorbent strip 12 within the plate A can be impregnated with any suitable or desired medicament before insertion between and enclosing 65 by the plies 10 and 11, or can be im-

pregnated as desired after completion of the plates, through apertures 14. In use in a shoe, the heel of a wearer rests upon the upper ply 10 of the plate and receives the medicament with which the felt or other 70 absorbent material strip 12 is impregnated, through the apertures 14, thus permitting treatment of the feet and body of a wearer through the heels in engagement with the heel plates A of the invention. The plate 75 A in use as above referred to is dished or depressed to form substantially a pocket therein, due to the pressure of a heel, and this can be employed to retain powdered or other types of medicaments for treating the 80 foot or body of a wearer of a shoe having a plate A mounted therein by absorption through the heel pores.

According to one form of the invention, 85 a pair of plates A are provided, with one of the plates formed of zinc and the other of copper, or any other two different metals capable of securing the desired results, and the absorbent material strips of the plates are impregnated with a suitable chemical. 90 In use a copper plate A is placed in the heel of one shoe of a pair, and a zinc plate A is placed in the other shoe.

From the foregoing description and explanation of the form of the invention illustrated by way of example in the accompanying drawings, it is seen that a heel plate is provided which forms a protection when mounted in position in a shoe, and further acts as a medicament carrier for treatment 100 of the feet and body through absorption of the medicament through the pores of a heel in engagement with and received by the plate. The broad principles and features of the invention can be mechanically expressed 105 in various other ways than by the form and embodiment presented and described here-with for purposes of example, and it is to be understood that it is not intended by this disclosure to restrict the invention to the exact construction of the plate A from the blank B, or to the specific formation and arrangement of the shoe engaging teeth 16 and apertures 14.

It is also evident that various changes, 110 modifications, variations and substitutions in details might be resorted to without departing from the spirit and scope of my invention, and hence I do not wish to limit myself to the specific detailed disclosure 115 hereof.

Desiring to protect my invention in the broadest manner legally possible what I claim is:

1. A heel protecting plate for shoes, comprising an upper ply forming a heel engaging surface, a lower ply forming a shoe contacting surface, the said upper and lower plies superposed and fixed together in plate forming relation, and forwardly extending 125 130

members depending from the lower ply and formed with free end portions adapted to engage a shoe in mounted position of the plate to prevent displacement by creeping.

5 2. A heel protecting plate for shoes, comprising an upper ply forming a heel engaging surface, a lower ply fixed to said upper ply and forming a shoe contacting surface, and absorbent material strip interposed between the upper and lower ply to provide a medicament carrier, apertures formed in the upper ply exposing said medicament carrier, and members formed from the lower ply having forwardly extending free end portions to engage a shoe and prevent displacement of the plate in use.

10 3. A heel protecting plate for shoes formed from a blank of soft metal bent over upon itself to provide upper and lower superposed plies, a strip of absorbent material forming a medicament carrier interposed and providing a yielding cushion between said plies, the said plies with the absorbent material strip interposed therebetween secured and 15 fixed together in plate forming relation, apertures formed in the upper ply for ex-

posing said strip, and the said soft metal upper ply pressed into shape conforming to and receiving a heel thereon in use.

4. In a removable heel protecting plate for 30 shoes, a series of tabs struck out from the plate and depending from the shoe engaging face thereof with their free end portions extended toward the forward end of the plate, the free end portions of said tabs 35 formed to engage a shoe to prevent creeping of the plate in use.

5. A heel protecting plate for insertion in and removal from shoes, embodying an upper ply and a lower ply of sheet metal fixed 40 together to form the plates, and a spaced series of substantially V-shaped tabs struck out from the lower ply and depending therefrom with their pointed free ends extended toward the forward end of the plate and 45 forming shoe engaging portions to prevent creeping of the plate from mounted position in a shoe.

Signed at McKenzie, Tennessee, this 15 day of June, 1923.

F. DAVID WALPOLE.
